UNITED STATES PATENT OFFICE.

FELTON M. LYTLE AND JOHN A. MCCOY, OF BALTIMORE, MARYLAND, ASSIGNEES TO HENRY B. LYTLE, OF BOSTON, MASSACHUSETTS, TRUSTEE.

TELEPHONE CENTRAL-OFFICE APPARATUS.

SPECIFICATION forming part of Letters Patent No. 294,482, dated March 4, 1884.

Application filed September 25, 1883. (No model.)

To all whom it may concern:

Be it known that we, FELTON M. LYTLE and JOHN A. MCCOY, citizens of the United States, residing at Baltimore, in the county of Baltimore and State of Maryland, have invented 5 certain new and useful Improvements in Telephone Central-Office Apparatus, of which the following is a specification, reference being had therein to the accompanying drawings.

10 Our invention relates to the central-office apparatus for sending and receiving calls to and from subscribers, and for connecting subscribers' lines, and also to apparatus whereby a chief operator may have supervision of all the 15 transactions of the switch-board operators in their intercourse with subscribers.

Our invention has especial reference to an improvement in that class of central-office apparatus in which pairs of connecting-cords are 20 used for connecting subscribers' lines, a fair example of such apparatus being shown in the United States Letters Patent granted to M. G. Kellogg, September 20, 1881, and numbered 247,199, while, however, the improvement is 25 upon this general class of apparatus, and is designed particularly for use in connection with multiple switch boards, as will hereinafter appear.

It has heretofore been necessary to use a signaling-key for each connecting-cord, in order 30 that signals may be sent from the central office to both a calling and a called subscriber, and in addition to these two keys a separate testing device has been necessary in multiple- 35 switch-board systems, in order for the operator to ascertain whether or not a called line is in use at some other table than his own or grounded for any purpose, the manipulation of this testing device adding to the work and 40. time required to be expended by the operator in making connections. It has further been customary to use a listening-key to connect each pair of cords with the operator's telephone when it is desired to ascertain if two 45 subscribers have finished conversation and have neglected to send the clearing-out signal. The use of such a listening-key is objectionable, from the fact that it grounds both subscribers' lines at the central-office while they 50 are connected for conversation, and a portion of the current is diverted from the lines, thus

seriously weakening the operation of the receiving-instruments.

The object of one part of our invention is to simplify the apparatus by enabling a single 55 pair of signaling-keys to be utilized for signaling with any number of pairs of connecting-cords, thereby greatly reducing the expense of construction and the liability of an operator's interrupting connected subscribers 60 by ringing on the wrong line, and, further, to dispense altogether with a separate listening-key.

Another part of the invention has for its object to utilize one cord of each pair for testing at multiple switch-boards, and thus dispense with a separate testing device for each 65 pair of cords.

Another part of the invention is designed 70 to enable a chief operator, located at any distance, to place his telephone in connection with the connecting-cords of any of a number of switch-boards, so as to overhear communications sent over any of the subscribers' lines to or from the central office.

75 With these objects in view our invention consists in certain novel combinations of devices and arrangements of circuits, which will be fully understood from the following particular description, in connection with the accompanying drawings, in which—

Figure 1 is a perspective view of a multiple switch-board equipped according to our invention, and Fig. 2 is a diagram illustrating the circuits of the board and the relation of 85 the various devices. Fig. 3 is a diagram illustrating the apparatus of a central office in which there are a number of switch-boards and a chief operator's apparatus.

Referring to Fig. 1, A is the multiple switch-board, the line-connecting sections of which or sub-boards are indicated by "No. 1" and "No. 2" and the annunciator-section is designated by name.

$b' b^2 b^3$, &c., designate the switch-plug holes. 90 $a' a^2 a^3$, &c., are the calling-annunciators, located in their proper section; and $c' c^2 c^3$, &c., are the clearing-out annunciators, located in their respective board-sections.

The letter d indicates a metallic ground-plate resting upon a desk or shelf of insulating material, through which and the ground-

plate are perforations for the passage of the connecting-cords F, each of which has one end connected with a metallic plug, as shown at f, the plugs of all the cords resting on the ground-plate d.

G and G' indicate two signaling-keys for use in connection with subscribers' lines, and G² and an annunciator, z, are used for signaling in connection with the chief operator's apparatus. Each of the board-sections, it will be seen, is provided with three signaling-keys and the chief operator's annunciator.

The letter T indicates the board-operators' transmitters, and T' their receivers. Upon the shelf in front of each numbered board-section is a multiple looping-in switch of the kind shown and described in the patent of H. W. Breckenridge, granted January 17, 1882, and numbered 252,421.

We will now refer to the diagram Fig. 2, in order to explain the connection of the various devices upon the switch-board, and first we will explain the construction of the multiple looping-in switch or series of looping-in switches upon the shelf. A series of metallic standards, p, is secured to the shelf, and to each of these standards is pivoted a jack, Q, provided with two curved arms projecting in opposite directions, so that they may be swung into contact alternately with metallic spring-arms R and R', which are secured to the shelf on opposite sides of each jack. Each of the spring-arms R' is provided with a curved extension, r, which hooks over a metallic rod, S, which is supported by suitable standards in such position that when the spring-arms R' are left free the inner surfaces of the hooked extensions r will bear against said rod; but when said arms are bent outward by the jacks being turned against them, no portions of said arms will be in contact with the rod. The connecting-cords F are arranged in pairs, there being five pairs shown in the diagram for each numbered section of the switch-board, though it will be understood that any number of pairs may be used that experience may show to be desirable. One cord of each pair is lettered f² and the other f³. The cord f² of each pair is connected to a jack, Q, of the multiple looping-in switch through a clearing-out annunciator, as shown at c c' c'', &c., and the other cord, f³, of each pair is connected with the hooked spring-arm opposite the jack to which the other cord of its pair is connected. The spring-arms R are all electrically connected together and to the key G, while the rod S is connected to the key G'. The upper contact g of the key G is connected with receiver T' through the transmitter, and the upper contact g' of the key G' is connected directly with the receiver. The lower contacts of the keys are connected together and to the ground through the generator X. The bases of the metallic plugs f rest upon a metallic ground-plate, d, and their plug-pins are adapted to enter the switches y in the usual manner. The subscribers' lines are indicated by l, l' l'',

&c., each line being connected through a series of connecting-switches from section to section of the board, and to a calling-annunciator, as is usual in multiple switch-boards.

In the diagram Fig. 2 the subscribers' lines l and l' are shown as connected through the left-hand pair of connecting-cords at the board-section No. 1.

The manner of receiving the call, giving the necessary signals, and making the connections is as follows: It will be understood that the jacks Q are normally turned against the spring-arms R', deflecting these arms so that their hooked extensions r are forced out of contact with the rod S. Now, when the annunciator-drop of line l' falls, the operator takes up the plug of the connecting-cord f² and inserts its pin in the switch connected with the line l', and at the same time turns the jack Q, connected with said cord, against its opposite spring-arm, R, and out of contact with the spring-arm R', so that the hooked extension of said arm is allowed to make contact with the rod S. A circuit is thus completed from the calling-subscriber's line through the cord f², jack Q, spring R, to key G, and from back (or upper) contact of key G through the transmitter and receiver, back contact of key G', thence by key G' to rod S, spring R', cord f³, its plug, and the ground, the normal position of keys G and G' being against their respective back or upper contacts. This circuit having been established, the operator, by means of his instruments, in the usual manner, ascertains with what line connection is wanted, and then makes the test to see if the called line is in use at any other board by touching the metallic frame y of the connecting-switch of line l' with the plug of the other cord, f³, of the pair, the cord f² of which he has already used. If the called line l' in the present instance should be connected for use at another table, there will be a clicking sound in the operator's receiver, as one side of said receiver will be connected to ground through the test-wire y', and the cord which is plugged to line l' at the other table or other connection from the switch-frames to ground, the other side of the receiver having been put to ground through the cord f² and the subscriber's line l'. It will be understood that the test-wire y' is connected with the frames y' of its series of connecting-switches; but it is insulated from the springs y'', to which the subscriber's line in its series is connected, and is only grounded by the insertion of a plug into one of the switches, such plug connecting the frame with the spring y'', so that the test-wire becomes grounded through the frame, the plug, the spring y'', and the subscriber's line connected to said spring. If, therefore, the clicking sound is produced at the operator's receiver on testing, as before stated, it is an indication that the called subscriber's line is plugged for some purpose to one of the connecting-switches in its series at some other board. If it is found that the called line is not in use,

this being indicated by the absence of a clicking sound at the receiver on testing, the operator inserts the plug in the switch, having it already in his hand and ready for insertion, 5 and then sends a call over the called line by pressing down the key G' upon its lower contact, which act, it will be seen, completes a circuit from the called line through the cord f^3 and its plug to spring-arm R' , with which 10 said cord is connected; the rod S , with which the hook r of said spring-arm is in contact; the key G' and the wire connecting it to the rod; the lower contact of the key, and thence through the generator X to the ground, the operator's telephone instruments being at the same time cut 15 out as the key leaves its upper contact. After giving the call the operator releases the key, which again rises to its upper contact, thus bringing the operator's instruments into connection with both of the subscribers' lines; but they can be immediately disconnected from these lines, as also can the keys G and G' , by simply returning the jack Q to its normal position, after which it will be seen that the circuit is 20 from the calling subscriber—say line l' —through the cord f^2 to the jack Q , and thence through the spring R' and over the cord f^3 to the called subscriber—say line l^3 —the two subscribers' lines being thus connected for conversation. 25 The connection having been completed, the two keys are free to be used in a similar manner with any other pair of the connecting-cords, as all the pairs of cords are connected with the multiple switch in a similar 30 manner, and thus two keys only are needed for all the pairs of cords, whereas two signaling-keys are required for each pair of cords at the switch-boards of this class, as heretofore constructed.

40 By the old plan of testing it was necessary to take up a separate testing device, make the test and replace it, and then pick up the connecting-cord and insert its plug at the switch if the called line was found free, while by our 45 improvement we economize in construction by dispensing with the separate testing device; and we save time and work for the operator, as when the called line is found free the plug is already at the point where it is to be inserted, and the operator is not required to replace one device and take up another.

50 It will be observed in the diagram Fig. 2 that a single battery-cell, x , is included in the loop with the receiver at each section of 55 the board, and it is the current of this battery which produces the clicking sound in the receiver when on testing a subscriber's line which is called it is found in use or connected for any purpose which would render another 60 connection with it improper.

It will now be observed that after the lines are connected and the jack returned to its normal position, the operator's keys G and G' and his transmitter and receiver are free to be used 65 in connection with any other pair of cords in receiving calls and making connections between any other two subscribers' lines in the

same manner that they have been used in connection with the pair of cords connecting lines l' and l^3 , and thus the two signaling-keys are 70 utilized for performing the same service which has required a large number of keys heretofore—that is, at least two keys with every pair of cords.

It will also be observed that when any two 75 lines are connected the operator can place his receiver in listening connection therewith by turning the jack Q , through which the cords are connected, so that it will contact with its opposite spring, R . The circuit in such case 80 having been already described, it is unnecessary to trace it again; but we would call attention to the fact that no ground-connection is made in thus establishing the listening-connection; but the receiver is simply looped into 85 circuit, so that none of the current is withdrawn from the connected lines, and the operation of their receivers is therefore not weakened or interfered with in any manner.

Referring now to the diagram Fig. 3, we will 90 explain the manner of connecting a number of switch-board apparatuses with the apparatus of the chief operator according to our invention. The several switch-boards are designated by numbers, and the letter V designates 95 the chief operator's table, upon which is located a multiple looping-in switch similar to that at each numbered section of the switch-board, but having a jack and contact-springs only for each operator. In this arrangement 100 a loop from each operator's receiver-circuit goes to the chief operator's table, one wire, w^2 , of said loop leading to a jack, Q' , of the chief operator's multiple looping-in switch, while the other wire, w^3 , leads to a hooked 105 spring-arm, R , opposite said jack. All the spring-arms R are connected through his transmitter T^2 to one binding-post of his receiving-telephone T^3 , the other binding-post of which is connected to the rod S of his multiple looping-in switch. It will now be seen that the 110 chief operator, by turning his jack in any loop, may bring his telephone-instruments in circuit with those of any operator at the switch-board, and he may thus overhear the operators' communications with subscribers. On each operator's table is a key, G^2 , having its upper contact connected with the ground through an 115 annunciator, z , and its lower contact to ground through a generator, X' . All the operators' 120 keys G^2 are connected to similar keys, G^3 , on the chief operator's table, having their upper contacts connected to the ground respectively through annunciators z' and their lower contacts connected to the ground through a generator, X^2 . It will be seen then that each operator, by these keys and annunciators, may call 125 the chief, and the chief may at any time call either of the operators.

In order that the chief operator's instruments and those of any operator may be put in connection for holding conversation, the chief simply turns his jack connected with the operators' instruments against its contact-

spring R, and a communicating circuit is thus completed from one side of the chief's transmitter over the wire w^1 , spring R, jack Q', wire w^2 , operator's receiver, thence through 5 his transmitter and key G, and thence through the spring-arms R and either of his jacks, which he should turn in contact with one of said springs, from this jack over its cord f^2 , and through the ground-plate to the other 10 cord of the pair, thence over the hooked spring-arm with which said cord is connected, and over the rod S, wire w , and to wire w^3 , which is part of loop to chief operator's multiple switch, rod S of said switch, wire w^4 , 15 through the chief operator's receiver, and to the opposite sides of his transmitter from whence the circuit started.

When conversation has been finished between the chief and one of the switch-board 20 operators, the parts are to be restored to their normal positions in the manner already described.

In the diagram Fig. 3 the chief operator's instruments are shown as connected for communication with the instruments of the operator at switch-board No. 1.

Having now fully described our invention, we wish it to be understood that we do not confine ourselves to the precise devices and 30 arrangement of circuits as shown in our drawings, but may vary the same in any manner for the better or more convenient carrying out of the essential principles of our invention.

The combination of the cords and metallic 35 plugs with a metallic ground-plate is intended to form the subject of a separate application for patent.

What we claim is—

1. The combination, with a series of pairs 40 of connecting-cords arranged to connect subscribers' lines and two signaling-keys, each having a contact-point connected with a generator, of a series of switches arranged to connect either of the pairs of connecting-cords 45 with said two signaling-keys, respectively, substantially as described.

2. The combination, with the series of pairs 50 of connecting-cords arranged to connect subscribers' lines, and two signaling-keys having contact-points, with which they are normally 55 in contact, connected to the opposite terminals, respectively, of a circuit including a telephone, and opposite contact-points, each connected with a generator, of a multiple looping-in switch and connections, arranged to place the cords of any pair separately in connection with said two keys, respectively, substantially as described.

3. The combination, with the series of pairs 60 of connecting-cords, of the multiple looping-in switch, having a separate jack or movable metallic part connected with one cord of each pair, a resilient contact-point in connection

with the other cord of each pair, a common conductor arranged to make contact with said 65 resilient contact-points when the latter are not in contact with the jacks, and to break contact therewith when in contact with said jacks, the opposite contact-points electrically connected together, the two keys connected 70 to said opposite contact-points and the common conductor, respectively, and the generator, arranged for connection with both of said signaling-keys, substantially as described.

4. The combination, with a pair of connecting-cords provided with metallic plugs and arranged for connecting subscribers' lines, of an electro-motive instrument—as, for instance, the operator's receiver—and a testing-battery arranged for operative intermediate connection with said cords, and a switch for effecting such connection, whereby, when such connection has been made and one of the cords plugged to a calling-line, the other cord is properly connected for testing another line, 85 substantially as described.

5. The combination of one or more pairs of connecting-cords, a telephone, a testing-battery connected with said telephone, and a switch and connections arranged to connect 90 said telephone and testing-battery simultaneously in circuit between the two cords of a pair, substantially as described, and for the purpose set forth.

6. The combination, with a series of switch-boards or switch-board sections, each provided with subscribers' line-terminals and pairs of connecting-cords, a multiple looping-in switch, two signaling-keys arranged for connection with the cords, and telephone-instruments, as described, of the chief operator's apparatus having a series of switches and a set of telephone-instruments arranged to be connected by said switches with the telephone-instruments of the switch-board operators, respectively, substantially as described.

7. The combination, with a series of switch-board apparatuses, each provided with pairs of connecting-cords and a multiple looping-in switch, two signaling-keys, and telephone-instruments, connected as described, of the chief operator's apparatus, provided with a multiple looping-in switch, having jacks connected in loops with the switch-board operators' telephones, hooked spring-arms connected also in 115 said loops, and the opposite spring-arms, and a conducting-rod connected with the opposite terminals of a circuit including chief operator's telephone, substantially as described.

In testimony whereof we affix our signatures 120 in presence of two witnesses.
